SHAMPOO CHAIR

Frederick Glaser, 1000 Lake Shore Plaza,
Chicago, Ill. 60611

Filed Jan. 19, 1970, Ser. No. 20,964

Term of patent 14 years

Int. Cl. D6—02

U.S. Cl. D15—3

FIG. 4

FIG. 1

FIG. 2

FIG. 3

FIG. 1 is a view in perspective of a shampoo chair showing my new design;

FIG. 2 is a front view of the shampoo chair of FIG. 1;

FIG. 3 is a side view of the shampoo chair of FIG. 1; and

FIG. 4 is a top view of the shampoo chair of FIG. 1.

The undisclosed back portion of the chair is plain and unornamented.

I claim:

The ornamental design for a shampoo chair, substantially as shown and described.
